UNITED STATES PATENT OFFICE.

CLEMENT LEE DOWNEY, OF CINCINNATI, OHIO.

COIN WRAPPER.

Application filed September 22, 1925. Serial No. 57,965.

My invention relates to coin wrappers in general and particularly to indicia for coin wrappers, which indicia will reveal the denomination of coins contained within the 5 wrapper.

It is the object of my invention to provide coin wrappers in which exposed indicia on the outer sides of the wrappers will reveal the sizes and diameters of coins contained 10 within the wrappers.

Specifically it is my object to provide coin wrappers with marginal stripes of one or more colors on the outer ends of the wrappers so that the stripes will be exposed to 15 view on the outsides of the wrappers, and so that the stripes may be seen from any side of the package. The wrappers are further provided with parallel stripes disposed on the outsides of the wrappers each one of 20 which shall be preferably of a different color and the stripes are disposed at such positions on the wrappers that when wrapped about coins of varying diameters, each indicating stripe will be aligned adjacent the marginal 25 stripe and will indicate the diameter and consequently the denomination of the coins within the wrapper.

In my Patent No. 1,379,751, of May 31, 1921, to which reference is hereby made, I 30 have disclosed a coin wrapper having orifices or windows on the outer folds of the wrapper which are adapted to register, depending on the circumference of the coins wrapped, with indicia in colors on inner 35 folds of the wrapper, which indicia denote the quantity and denomination of the coins within the package. It is the object of my present invention not only to provide a coin wrapper which will indicate the denomination 40 of coins within a package because of its own structure, but which will, in combination with a wrapper having registering windows or orifices doubly decrease the likelihood of error arising with the use of my 45 wrappers.

Referring to the drawings in which I have illustrated a preferred type of wrapper with marginal and indicia stripes disposed diagonally across the wrapper:

50 Figure 1 shows a plan view of a wrapper.

Figure 2 is a perspective view of a wrapper rolled up to as to enclose a stack of half dollars.

55 Figure 3 is a perspective view of the same wrapper indicated in Figures 1 and 2 as it

would appear when rolled up so as to enclose a stack of quarters.

Generally indicated at 1 is the wrapper for coins which may be of any desired shape, but which I have illustrated as having one 60 straight side and one diagonally cut side. The wrapper is printed with a marginal stripe 2, which extends across the diagonally cut side so that when the wrapper is rolled about a stack of coins the straight side of 65 the wrapper will be applied to the coins and the diagonally cut side will come on the outside of the roll in which position it will appear as extending down across a wrapped coin stack as shown in Figures 2 and 3. 70

I have indicated that the marginal stripe 2 is black, but it will be obvious that any other standard color will be equally as suitable. Extending down across the wrapper are the indicia stripes 3, 4, 5, 6 and 7, each 75 stripe being colored differently as indicated in the drawings, in which the stripes are purple, blue, green, red and yellow reading from left to right respectively. When the wrapper is rolled about a stack of half dollars the purple indicating stripe 3 will lie adjacent the black marginal stripe 2 as shown in Figure 2. When the wrapper is rolled about a stack of quarters the blue indicating stripe 4 will lie adjacent the black marginal 80 stripe 2 as indicated in Figure 3. Thus no matter what coin is rolled in the wrapper on the outer side, an indicia stripe lying adjacent the marginal stripe will show from all 85 sides of the package, what the denomination 90 is of the coins within the wrapper.

The principle involved is the disposal of the colored indicia stripes at such positions on the outer side of the wrapper that the distance from the left hand side of the indicia stripe to the right hand side of the marginal stripe in a line parallel with the direction, in which the wrapper is to be rolled about the coins shall be approximately equal to the outer circumference of 95 the particular coin which the indicia stripe is supposed to indicate, with sufficient additional allowance for the thickness of the several layers of the wrapper.

While I have shown a wrapper with the 105 right side cut diagonally, my method of disposing the indicia and marginal stripes is equally adaptable for use with a wrapper with the right side cut at a right angle to the length of the wrapper. In such a case 110

the marginal stripe will extend across the wrapper at right angles to the length and the colored indicia stripes will be parallel to the marginal stripe, but will be spaced 5 differently to allow for the difference in the periphery of a wrapper rolled in a direction at right angles to the indicia stripes and one rolled in a line forming an obtuse angle with the indicia stripes.

10 On the indicia lines I preferably provide suitable printing such as for example "Ten dollars in halves" to be printed on the purple stripe 3, and "Ten dollars in quarters" on the blue stripe 4. I also preferably print 15 on the marginal or registering stripe 3 the inscription "Contains amount shown at this line". The printing of suitable descriptive matter will be entirely according to the re-

quirements of the purchasers of the wrap-
pers.

It will further be obvious that by chang-
ing the position of the indicia stripes in ac-
cordance with the variation in circumference
of coins to be wrapped, that my invention
will be adaptable for use with foreign coins 25

as well as with coins of the United States.

Having thus described my invention, what
I claim as new and desire to secure by Let-
ters Patent, is:—

A coin wrapper adapted to be rolled about
a stack of coins, a diagonal marginal stripe
on the wrapper and diagonal indicia stripes
adapted to register adjacent the marginal
stripe, each of the indicia stripes indicating
a stack of coins of a different denomination.

CLEMENT LEE DOWNEY.
